ABSTRACT: A process for the cathodic alkylation of lead using ethyl chloride, methyl chloride, or mixture thereof as an alkylating agent and iodide ion as an electrochemical catalyst with a liquid-liquid junction of propylene carbonate and water wherein propylene carbonate is in the catholyte and water is in the anolyte.

CATHODIC PROCESS FOR THE PREPARATION OF TETRAALKYL LEAD COMPOUNDS

BACKGROUND OF INVENTION

1. Field of Invention

This invention relates to the preparation of tetraalkyl lead compounds and more particularly to an electrolytic process wherein an alkyl chloride is reduced at a lead cathode.

2. Description of Prior Art

Electrolytic processes for the production of alkyl leads are known. For example, Calingaert and Mead disclosed tetraalkyl lead formation at a lead cathode by electrolyzing a catholyte consisting of an alkyl halide in either alcoholic caustic (Calingaert in U.S. Pat. No. 1,539,297) or aqueous caustic containing casein (Mead in U.S. Pat. No. 1,567,159). Also, Silversmith et al. disclosed a process for preparing tetraalkyl lead compounds by electrolyzing at a lead cathode, a solution of an alkyl halide in a normally liquid, nonhydroxyllic catholyte (Silversmith in U.S. Pat. No. 3,197,392). The most recent disclosure in this field appears to be a patent to Smeltz which discloses a process for producing tetraalkyl lead compounds at a lead cathode in an electrolytic cell having a catholyte containing an alkyl halide, a tetraalkyl ammonium monohalide current carrier and from about 1 to about 20 moles of water per mole of said current carrier (Smeltz in U.S. Pat. No. 3,392,093).

SUMMARY OF INVENTION

According to this invention an alkyl chloride is reduced at a lead cathode in a catholyte containing propylene carbonate and in the presence of an iodide ion acting as an electrochemical catalyst and with an anolyte containing water.

DETAILED DESCRIPTION

Tetramethyl and tetraethyl lead can be prepared electrochemically either by anodic oxidation or by cathodic reduction. The existing anodic processes demand the use of very expensive alkylating agents such as Grignard reagent or alkyl aluminum compounds. In addition the required solvent systems are hazardous and low conducting. These shortcomings greatly aggravate the final process cost.

In cathodic process, alkyl halides are usually employed as alkylating agents:

where R denotes CH_3 or C_2H_5 , and X denotes a halogen. Here one at once encounters a fatal shortcoming which is common to all of the presently patented processes. Even though the current efficiency is very good when alkyl iodide or alkyl bromide is employed, the efficiency with chloride is so low that in this latter case there is very little, if any, chance of commercial success. Bromides and iodides are very expensive; in addition, a bromine or iodine recycle route that can be readily adopted to electrochemical process is not known at present. As it stands now, then, none of the known cathodic process is likely to compete with the nonelectrochemical process in which sodium-lead alloy is employed.

We disclose a new cathodic process which is free from the above shortcomings. Briefly, what is new in our process is:

- The use of an electrochemical catalyst with which alkyl chloride can be reduced with high current efficiency, and
- The use of a new solvent system in which a stable liquid-liquid junction is established.

The electrochemical process for the production of alkyl leads and chlorine using alkyl chloride and lead according to the equation:

poses some technological problems. These are:

- One must find a proper cathodic solvent and cathodic conditions to carry out the cathodic reduction (1). The required solvent properties are: high-dielectric constant, appreciable solubility of inert electrolytes, and high-reduction potential so that the solvents themselves do not undergo reduction before reaction (1) occurs.

B. The anodic solvent should be inert to chlorine. Other requirements are: high-dielectric constant, appreciable solubility of some salt containing chloride anion, and a high-oxidation potential so that the oxidation reaction:

proceeds before the oxidation of solvents themselves occurs.

C. Proper partitioning agents, such as ion permeable membrane, which are inert to both anodic and cathodic solvents, must be found to separate anolyte from catholyte.

The key concepts in our process are (1) the use of I^{7E} ion as an electrochemical catalyst, and the use of immiscible liquid-liquid junction to separate catholyte from anolyte. As far as we are aware, the use of these concepts in the electrochemical production of alkyl leads is entirely new. The iodide ion can be added in the form of sodium iodide or potassium iodide.

In propylene carbonate the following nucleophilic substitution reaction,

occurs readily and cleanly. As shown later, ethyl iodide in propylene carbonate can be reduced with 100 percent current efficiency:

From (4) and (5), we note that the net result is the reaction of alkyl chloride and Pb to produce alkyl leads. No net consumption of iodide ion occurs. In view of these facts, we presume that the catalytic property of iodide ion in our process is due to the nucleophilic substitution reaction.

As mentioned earlier, another key concept in our process is the use of immiscible liquid-liquid junction to separate anodic solvent from cathodic solvent. The propylene carbonate-water mixture forms two immiscible liquid layers. The bottom phase

is mostly propylene carbonate and the small amount of water is this layer which can be reduced to less than few percent by adding alkyl halide is not harmful in the cathodic process. The concentration of propylene carbonate in water layer very strongly depends on the concentration of salts as well as the amount of alkyl halide in the propylene carbonate layer. For example, in the pure propylene carbonate-pure water system the water layer contains as much as 22 weight percent propylene carbonate. This can be, however, reduced to less than few percent by adding sodium sulfate. The important fact in our application is that once equilibrium is established the further diffusion of cathodic and anodic solvent does not occur. Since water can now be used as an anodic solvent, the generation and recovery of chlorine poses no problem.

Even though propylene carbonate has been used before as an electrolytic solvent, the possibility of using the immiscible liquid-liquid junction in electrochemistry has not been explored. Immiscible liquid junction cannot be set up between propylene carbonate and alcohols which are typical hydroxyllic solvents but is readily set up with water. Example 1 below demonstrates the use of the above two key concepts in the production of alkyl lead.

EXAMPLE 1

A Pyrex cell with glass frit divider was used as an electrochemical cell. The catholyte composition was: Propylene carbonate—100 g., C_2H_5Cl —20 g., and NaI —50 g. This mixture was heated to 60° C. for 6 hours, and white precipitate was filtered off. More NaI was added to saturate the solution. Fifty cubic centimeters of the resulting solution was charged in the cathode compartment. A flat Pb cathode had an approximate area of 3 cm.². Anolyte composition was: 100 g. water, 10 g. $NaCl$, and 15 g. Na_2SO_4 . Carbon anode was employed. The whole cell was then blanketed with 5 p.s.i. CH_4 , and electrolysis was carried out at a controlled constant current of 100 ma. for 4 hours. The TEL formed was extracted with hexane and was analyzed chromatographically. Results:

$$\begin{aligned} \text{moles TEL formed} &= 3.99 \times 10^{-3} \\ \text{Percent current efficiency} &= 107 \\ \text{grams Pb lost} &= 0.7826 \end{aligned}$$

Percent current efficiency = 101

The error involved in chromatographic analysis undoubtedly led to the percent efficiency greater than 100 percent; in any case, TEL yield is nearly quantitative. In this experiment, the sodium sulfite in the anode was used to scavenge Cl_2 . It is obvious that Cl_2 can be recovered as a gas, or may be reacted in situ with various other compounds, such as ethylene.

We also made several attempts to produce TEL without using I^{7E} catalyst, but otherwise under the same experimental conditions as in example 1. In C_2H_5Br -LiBr system, TEL yield was only 40 percent; this is too low to be of any commercial interest. In C_2H_5Cl -LiCl system, TEL yield was negligibly small. These results clearly indicate that iodide ion is an indispensable catalyst.

EXAMPLE 2

The composition of catholyte in this was propylene carbonate—100 g., C_2H_5I —20 g., NaI —10 g. while the anolyte composition was H_2O —100 g., NaI —10 g., Na_2SO_3 —15 g. Other details are given in example 1. The result: percent current efficiency based on TEL formed = 103.5.

EXAMPLE 3

In this example, we made an attempt to test some of the previously used solvent systems to prepare TEL using C_2H_5I and sodium iodide. We found that CH_3OH yielded 39 percent current efficiency, while in ethanol and propanol current efficiency was less than 10 percent. Acetonitrile used in bromide systems was found to be entirely unsatisfactory for the present case because, under the same conditions used in example 2, there occurred gas formation at the cathode. These results indicate that the propylene carbonate-water system with immiscible liquid junction is much superior to various other solvent

systems employed before.

Having this described the invention by providing specific examples thereof, it is to be understood that no undue restrictions or limitations are to be drawn by reason thereof and that many modifications and variations are within the scope of the invention.

What is claimed is:

1. In an electrolytic process for producing tetraalkyl lead compounds at a lead cathode in an electrolytic cell having a lead cathode, an anode of a material which is resistant to attack by halogens, and a current-permeable partition separating the catholyte from the anolyte which process comprises:
  - A. passing an electrolyzing direct current through a liquid catholyte comprising
    - a. an alkylating agent of ethyl chloride, methyl chloride or mixtures thereof,
    - b. propylene carbonate,
    - c. an alkali metal iodide; and through a liquid anolyte comprising
      1. water, and
      2. a current carrying salt; and
    - B. recovering tetraalkyl lead from the catholyte; the improvement comprising heating said liquid catholyte solution to about 60° C. for about 6 hours prior to passing said electrolyzing current.
  2. The process of claim 1 wherein said alkali metal iodide is sodium iodide or potassium iodide.
  3. The process of claim 1 wherein said current carrying salt in the anolyte is sodium chloride or potassium chloride.
  4. The process of claim 1 wherein said alkylating agent is ethyl chloride.
  5. The process of claim 1 wherein said alkylating agent is methyl chloride.
